HIS ATTORNEY.

UNITED STATES PATENT OFFICE.

LEO PRANGE, OF BROOKLYN, NEW YORK.

DESIGN FOR A BUTTON.

SPECIFICATION forming part of Design No. 21,321, dated January 26, 1892.

Application filed December 18, 1891. Serial No. 415,555. Term of patent 3½ years.

To all whom it may concern:

Be it known that I, LEO PRANGE, of Brooklyn, Kings county, and State of New York, have originated and produced a new Design 5 for Buttons, of which the following is a specification.

I will describe a button embodying my design.

In the accompanying drawings, Figure 1 is 10 a front view of a circular button embodying my design. Fig. 2 is a perspective side view thereof.

My design comprises a circular row of jewel-like figures A, surrounding an elliptical or ellipsoidal figure B, which is located so as to be 15 in close proximity with one portion of the circular row of jewel-like figures A. The crescent-shaped surface C, intermediate of the elliptical or ellipsoidal figure B and the opposite

portion of the circular row of jewel-like figures A, is shown as ornamented with wavy circular lines. It will be seen that the elliptical or ellipsoidal figure has its margin defined by the representation of a rope or cord D, and that within this figure is a group of jewel-like figures E.

What I claim, and desire to secure by Letters Patent, is—

The design for a button, as herein shown and described.

In testimony whereof I have signed my name to this specification in the presence of two subscribing witnesses.

LEO PRANGE
